UNITED STATES PATENT OFFICE.

DAVID E. SKEDGELL, OF FALL RIVER, MASSACHUSETTS, ASSIGNOR TO DRAPER CORPORATION, OF HOPEDALE, MASSACHUSETTS, A CORPORATION OF MAINE.

CUSHION-SPRING SHUTTLE-CHECK.

1,341,941.

Specification of Letters Patent. Patented June 1, 1920.

Application filed July 1, 1918. Serial No. 242,944.

To all whom it may concern:

Be it known that I, DAVID E. SKEDGELL, of Fall River, in the county of Bristol and State of Massachusetts, have invented certain new and useful Improvements in Cushion-Spring Shuttle-Checks; and I do hereby declare the following to be a full, clear, and exact description of the invention, such as will enable others skilled in the art to which it appertains to make and use the same.

This invention relates to checks for picker sticks of looms, and is an improvement upon the check set forth in United States Letters Patent of Rhoades, No. 1,119,764, December 1, 1914. The objects of the improvement are to guide the check strap both above and below, to reduce wear on the check strap, and to simplify the spring tension.

In the drawings, Figure 1 shows a portion of the front of a loom with the improved check applied thereto. Fig. 2 is a horizontal sectional view on line 2—2 in Fig. 1. Fig. 3 is a vertical sectional view on line 3—3 in Fig. 1. Fig. 4 is a detail illustrating the tension adjustment.

The lay 1, shuttle box 2, shuttle 3, picker 4, and picker stick 5 are of known construction and operation.

The improved checking mechanism includes a pair of brackets 8 which form a support and guide for an endless check strap 9 within which and between the two brackets the picker stick 5 travels. Each bracket extends downwardly from the lay to which both brackets are secured by a single bolt 10 passing through the lay and a hole 11 in each bracket, and by a screw 12 for each bracket. Each bracket has a longitudinally extending plate 13 which is curved inwardly at each end thereby providing a rounded surface conforming to the curvature of the check strap, so that wear on the strap is reduced to a minimum. Each plate has upper and lower outwardly and longitudinally extending horizontal flanges 14 and 15 throughout its length between which the check strap 9 is maintained and guided in horizontal position. The check strap is pressed toward each plate by the free end of a flat steel spring 17, which extends inwardly from a supporting angle iron 18 which is adjustably connected to a laterally projecting arm 19 of the corresponding supporting bracket. As shown in

Fig. 4, the upper horizontal arm 20 of the angle iron 18, is slotted at 21, to receive a headed bolt 22, which extends through an open slot 23, in the arm 19. These slots permit the adjustment of the angle iron, and a nut 24 on the bolt maintains the adjustment. Hence the tension of each spring on the check strap can be regulated so as to furnish the desired resistance to the picker stick.

In the use of this checking mechanism, the picker stick is smoothly checked as it nears the end of its stroke in both directions by engagement with the endless check strap which then moves with the stick throughout the remainder of its stroke, the freedom of this movement being controlled by the tension of the springs 17. The check strap is of just sufficient length to permit the proper range of movement of the picker stick. By this checking mechanism a perfect checking of the shuttle is insured. It will be noted that all parts of the brackets with which the check strap engages are so formed as to produce a minimum wear of the band.

I claim—

1. A picker check for looms, including, in combination with a picker, a picker stick, a longitudinally movable endless check strap with which said picker stick engages near the ends of its strokes, supporting brackets for said strap at each side thereof, each bracket having a longitudinally extending plate with outwardly extending guide flanges, one above and the other below the check strap, and each plate curving inwardly at each end, and a flat spring adjustably secured to each bracket and pressing at its free end on the check strap.

2. A picker check for looms, including, in combination with a picker, a picker stick, a longitudinally movable endless check strap with which said picker stick engages near the ends of its strokes, supporting brackets for said strap at each side thereof, each bracket having a longitudinally extending plate with outwardly extending guide flanges, one above and the other below the check strap, and a flat spring adjustably secured to each bracket and pressing at its free end on the check strap.

In testimony whereof, I have signed this specification.

DAVID E. SKEDGELL.
